UNITED STATES PATENT OFFICE.

EMMA SONNTAG, OF REDLANDS, CALIFORNIA.

CORSET.

1,303,512.

Specification of Letters Patent. Patented May 13, 1919.

Application filed January 11, 1915. Serial No. 1,696.

To all whom it may concern:

Be it known that I, EMMA SONNTAG, a citizen of the United States, residing at Redlands, in the county of San Bernardino 5 and State of California, have invented a new and useful Corset, of which the following is a specification.

An object of this invention is to provide a corset that will fit the form and support the bust and particularly the mammae more perfectly and with finer and more graceful lines than heretofore; to give greater ease and comfort to the wearer; and to avoid danger of undesirable pressure upon the 15 mammae which might hurt or harm the same.

It has been customary heretofore to terminate the upper end of the corset at a point below the utmost swell of the bust 20 with the consequence that where such corsets are well fitted to the person while standing it often occurs that when the person is seated the corset presses up against the breasts which if full are apt to crowd out 25 and overhang the upper edge of the corset which in turn presses into the breasts causing more or less discomfort and pain and possible injury.

A feature of this invention is the provision of a flexible inwardly curved extension 30 above the level of the upper ends of the fastening ribs of the corset in connection with a flexible side stay for the purpose of sustaining and confining the bust sufficiently 35 to prevent it from protruding over the upper ends of the corset ribs or stays.

The corset is also constructed to overhang inwardly, being curved over and made to conform to the upper side of the mammae so 40 as to give a natural form to the figure of the wearer.

Other features of the invention reside in means for producing more flexibility to front-laced corsets in combination with 45 with means for connecting and disconnecting the edges, whereby greater ease of fastening and unfastening the corset is secured; and likelihood of protrusions of flesh through the lacing are avoided, and 50 appearance of flatness at the front of the abdomen is effected, thus giving better lines to the form.

In carrying out this invention in its preferred form for a front lace corset, lacing 55 strips having means such as clasps, hooks and eyes or the like for detachable connec-

tion with each other, are provided between the front edges of the corset body, and each of such strips is laced to an edge of such body thus to locate the clasp ribs or stays 60 centrally of the front lace corset.

The invention may be carried out in various forms.

Other objects, advantages and features of novelty may appear from the subjoined detail description.

The accompanying drawings illustrate corsets constructed in accordance with this invention.

Figure 1 is a front view of a front lace 70 corset constructed in accordance with this invention and arranged on a form for clear illustration of novel features, one upper extension flap of the corset being laid open for clearness of illustration.

Fig. 2 is a side elevation of the corset shown in Fig. 1.

Fig. 3 is an enlarged fragmental detail of the corset shown in Fig. 1.

Fig. 4 is a front view of a back-lace cor- 80 set embodying features of the invention.

Fig. 5 is an enlarged fragmental sec- tional detail of a part of the corset shown in Fig. 4.

Referring first to the form shown in Figs. 85 1, 2 and 3, the fastening or clasp ribs 1, 2 of the corset may be constructed of steel or any other suitable material and may be provided with the usual form of fastening means or clasps 3, 4, and are of the usual 90 length; terminating at a point not higher but generally somewhat lower than the utmost swell of the bust. These fastening ribs may be fastened to the body members 5 of the corset by any suitable means such as the 95 floating lacing strips 18 and laces 6 in Fig. 1 or may be directly incased in the material of said body portions as in Fig. 4.

An upper extension of the corset is provided above the level of the upper ends of 100 the fastening ribs and such extension may be in the form of swinging flaps 7 connected by upward side extensions 8 with the main body members 5. These flaps may be vari- 105 ously formed and preferably provided with highly flexible stays 9 extending up and down and conforming or conformable to the upper surface of the bosom. Preferably the fastening ribs terminate below the level of the mammae and their upper ends are over- 110 lapped by the mammae cover members. This construction is such that the mammae

will not be engaged by the fastening ribs when the person bends forward and yet the mammae will be perfectly supported. Where a corset is designed for a person having a full bust the up and down stays are sufficient to hold the shape of the upper extension and to prevent the material from rumpling; but where the bust of the wearer is not full and it is desired to supply bust form, transverse stays 10 are provided to maintain the desired curved form. Said stays are of a highly flexible nature so that the corset at the fullest swell of the bust will be soft and flexible although capable of maintaining a rounded and full form.

A puff lining 11 of shirred sheer material may be fastened in the concave inner side of the upper extension to sustain the form without material weight or heat.

20 The meeting edges of the flaps may be secured together by any suitable fastening means as by the laces 12 or by the usual hooks, or buttons and eyes.

In the Figs. 1, 2 and 3 and also in Figs. 25 4 and 5, I have shown a corset comprising a body as at 5 or 5' and a mammae cover a, said body having straight front edges b and having its upper edges c sloping outward from the front center above the mammae 30 cover a to the middle under-arm d, and in each form means are shown to connect said straight front edges to each other, the form shown in Figs. 1, 2 and 3 differing from that shown in Figs. 4 and 5 in that the edges b 35 are not directly connected with each other, but are connected by the floating lacing strips 18 and the lacings 6. Flexible side stays e are provided, connected to the corset body and extending over the groin f to the upper edge c of the corset body, the upper portion of said stay e being curved to conform to the mammae at the rearward sides of the mammae cover a and in front of the under-arm portions d, thus constituting lateral supports for the mammae cover and mammae and avoiding obtrusion and protraction of the upper edge of the corset, and preventing the mammae from falling forward.

50 The corset body in Fig. 1 is formed with straight edge front wings extending above the lacings 6 and the straight side stays e, that is to say, extending from in front of said side stays to beneath the mammae, the upper portion of said body being formed as flaps 7 extending centrally away from said stays and extending above and below the mammae and overlapping the wings, and the means as the lacings 6 and floating lacing stays 18 which connect said wings together serve to hold the mammae from lapsing over and from being pinched between relatively moving parts of the corset when the person of the wearer is bent forward or 60 sidewise or in any other direction.

In the form shown in Figs. 1 and 2 a flexible inner upward extension 13 is provided by extending the material of the corset body wings upward above the level of the ribs, the flaps being adapted to lap over and 70 cover the inner extensions and upper portions of the bodies 5 when the flap edges are fastened together.

In the forms shown in Figs. 4 and 5 each of the extensions 14 is a direct upward extension 75 of the corset body 5' with highly flexible stays 15 above the upper end of the fastening ribs as in the form shown in Figs. 1 and 2. The upward extension is provided with highly flexible edge fastening stays 16 80 and the meeting edges of said extensions are joined together by any suitable means as with the other form.

In the form shown in Figs. 1 and 2 each of the body members 5 has lace receiving 85 means in the form of eyelets 17 along one edge.

Two separate floating lacing strips 18 are provided, each having lace receiving means, as the eyelets 17, all along one edge; and 90 each having engaging means as the usual fastening ribs 1, 2, with clasps 3, 4, along a part of the other edge. Said lacing strips 18 are flexible for a considerable distance below the steel fastening ribs 1, 2, and are 95 provided with fastening means as common hooks and eyes 19 or laces, not shown, for connecting the lower parts of the two lacing strips together.

The lacing strips are fastened to the lace 100 receiving fastening edges of the corset body by the laces 6 and when the fastening ribs 1, 2, are fastened together on the person of the wearer by their fastening means, the front of the corset will more perfectly conform to 105 the person of the wearer and the fastening ribs 1, 2 can be brought to the front center and in line with the depression between the breasts where there is no danger of these 110 comparatively stiff stays or ribs 1, 2 striking upon either breast as such fastening ribs would be likely to do when the wearer is seated or bends forward if the ribs were not centrally located.

That is to say, in case the clasp ribs of 115 front lace corsets are located at the side of the front midline they are apt to strike the mammae of the wearer having a full bust and this difficulty is entirely obviated by locating the fastening ribs centrally.

The take-up space 20 between the fastening ribs 1, 2, of the straight front edges b of the corset body may be of any required widths respectively, to adjust the fastening ribs to central position for different forms. 120

The short inner upward highly flexible extensions 21 and 22 are provided at the tops respectively of the strips 18 and the upward extension 22 of the fastening edges or front wings b extend above the level of the fasten- 125 130

ing ribs thus to bend inward and conform to the bust when the outer upward extensions are fastened in place.

5 The flexible stays *e*, 9 and 10 are the usual highly flexible stays provided in high priced corsets now on the market and the clasp stays or ribs 1, 2 are preferably any good quality steel clasp stays that are somewhat more flexible at the upper than at the lower

10 ends.

Where a very flexible front is desired, more flexible fastening ribs than those made with the clasps may be employed, and hooks and eyes sewed to the rib incasing material

15 of the corset may be used to fasten the fastening edges together.

It is understood that various changes of construction may be made without departing from the spirit of the invention and that 20 the invention is pioneer in providing the inwardly or rearwardly overhanging upward front extension of either the form shown in Figs. 4 and 5 or the flap form shown in Figs. 1, 2 and 3.

25 The hollow flexible side stays as at *e* are fixed to the body of the corset and extend over the groin upward and at the rear of the mammae and are bent at their upper ends so as to conform to the swell at the bust just 30 at the rear of the mammae. These side stays support the mammae covers and assist in giving form to the mammae covers and prevent them from exerting undue pressure upon the mammae and they are connected 35 with the lacing stays 9 by cross stays 10.

In case flaps are employed these side stays support rear edges of the flaps and the horizontal stays 10 bridge the space between the side stays and the lacing stays. By this 40 construction and arrangement it is made possible to comfortably cover the mammae either with flaps that may be swung apart or with a cover as in Fig. 4 that is not separated from the main body of the corset.

45 I claim:—

1. A corset comprising a body and a mammae cover, each having straight front edges and the mammae cover having its upper

edges sloping downward from the front center to under the arm; means to connect 50 the straight front edges of the body to each other; means to connect the straight front edges of the mammae cover members to each other; straight flexible side stays extending from the groin to the upper edge of the corset, the upper portions thereof being at the rearward sides of the mammae cover and in front of the arms, thus constituting lateral supports for the mammae and avoiding obtrusion and protrusion of the upper edge of 60 the corset and preventing the mammae from falling forward.

2. A corset comprising a body and a mammae cover, each having straight front edges; said mammae cover having its upper edges 65 sloping downward from the front center above the mammae cover to under the arm; means to connect the straight front edges of the corset body to each other; means to connect the straight front edges of the mammae 70 covers to each other; straight flexible side stays extending from the groin to the upper edge of the corset, the upper portions thereof being at the rearward sides of the mammae covers and in front of the arms, thus 75 constituting lateral supports for the mammae and avoiding obtrusion and protrusion of the upper edge of the corset and preventing the mammae from falling forward; said corset body being formed with straight- 80 edged front wings extending from or in front of said stays to beneath the mammae; the upper portion of said corset body being formed with flaps extending centrally away from said stays and extending above and be- 85 low the mammae, and overlapping the wings and constituting the mammae cover and the means which connect said wings together.

In testimony whereof, I have hereunto set my hand at Los Angeles, California, this 90 4th day of January 1915.

EMMA SONNTAG.
